COLLAPSIBLE TIE RACK

Filed Sept. 3, 1947

UNITED STATES PATENT OFFICE

2,474,436

COLLAPSIBLE TIE RACK

Philip Pestynier, Jamaica, N. Y., assignor to Ty-Master Corporation, New York, N. Y.

Application September 3, 1947, Serial No. 771,839

3 Claims. (Cl. 211—104)

1

This invention relates to an improved rack for hanging ties, and more particularly to a collapsible tie rack attachable to a supporting surface.

It is an object of the present invention to provide a tie a rack of simple construction adapted for carrying a large number of ties, the ties being easily accessible for selection by the wearer at all times.

Another object of the invention is the provision of a tie rack which may be easily installed on a wall, the inside of a closet door or any other suitable supporting surface, the tie rack being collapsible inwardly toward said supporting surface to occupy a minimum of space when not being actively used for the selection of ties.

A further object of the invention is the provision of a tie rack of the character indicated which may be fabricated from a minimum number of parts at low cost.

The foregoing objects, as well as additional objects and advantages of the invention will be readily apparent in the course of the following detailed description taken in connection with the accompanying drawing which illustrates a preferred embodiment of the invention, and wherein:

Fig. 1 is a perspective view of a tie rack embodying the features of the invention, mounted on a supporting surface, and shown in operative, extended position.

Fig. 2 is a front elevational view of the tie rack.

Fig. 3 is a top plan view of the tie rack in its operative, extended position, the tie rack being swingable about a pair of mounting lugs to a collapsed position of small compass, as indicated by the fragmentary broken outlines.

Fig. 4 is a side elevational view of the tie rack in operative, extended position.

Referring now to the drawing in greater detail, the tie rack comprises a pair of supporting members or bars 10, each of which has a mounting lug 11 pivotally secured as by pivot pins 12 at the inner end thereof. Each mounting lug 11 has an aperture 11a therein for securing the tie rack to a supporting surface as by means of screws 13. An outer longitudinal element or bar 14 is pivotally connected at the outer end of each supporting member 10 extending between said pair of supporting members, and preferably disposed below said supporting member by a pair of spacers 15. A plurality of hanger pins 16 is fixed to longitudinal element 14 and spaced therealong for hanging ties. Hanger pins 16 preferably extend

2

outwardly from said longitudinal element and are turned upwardly at their free ends as at 16a, in order to accommodate a maximum number of ties, and eliminate any possibility of the ties slipping off said hanger pins.

An inner longitudinal element 17 is pivotally supported by the pair of supporting members 10 intermediate their ends, said inner element being preferably disposed above said supporting members by a pair of spacers 18. A plurality of spacing pins 19 are fixed along the top surface of longitudinal element 17 to define separate sections 17a therealong for hanging additional ties.

After the tie rack has been mounted on a supporting surface W by means of screws 13 passing through apertures 11a in mounting lugs 11, ties may be hung not only along the inner longitudinal element 17, but additional ties may be suspended from hanger pins 16 of outer longitudinal element 14, as clearly illustrated in Fig. 1.

The disposition of inner longitudinal element 17 above supporting members 10 and the disposition of outer longitudinal element 14 below said supporting members contributes greatly to the ease of selecting a particular tie by allowing rapid visual inspection of the ties on two different levels, a portion of the ties on the upper, inner longitudinal element 17 being clearly visible even when the hanger pins 16 of lower, outer longitudinal element 14 are filled to capacity with ties.

An important feature of the invention resides in the adaptability of the tie rack to be collapsed or swung inwardly toward the supporting surface W to lie within a narrow compass thereagainst, and occupy a minimum of space when not being actively used for the selection of ties. Thus, by pushing against either end of the tie rack, as indicated by the arrows in Fig. 3, supporting members 10 are caused to swing inwardly toward the supporting surface W about their respective pivotal connections 12 to mounting lugs 11. The parallel inner and outer longitudinal elements 17 and 14 will simultaneously move inwardly toward supporting surface W, being swingably supported between said supporting members 10. The ultimate collapsed position of supporting members 10, inner longitudinal element 17 and the outer longitudinal element 14 will be substantially flat against the supporting surface W, being limited only by the thickness of the ties suspended from said inner longitudinal element. An intermediate position of the tie rack in its inward displacement toward the supporting surface W is shown in fragmentary broken outline in Fig. 3. The tie rack may be easily converted from the col-

apsed position of narrow compass to the extended position of Fig. 1, by pulling on outer longitudinal element 14, in which latter position any particular tie or ties may be removed from or placed on the rack.

The tie rack may be fabricated from any metal or other suitable material at extremely low cost because of the simplicity of design and construction.

Since certain modifications may be made in the tie rack of the invention without departing from the scope thereof, it is intended that all matter contained in the foregoing description and shown in the accompanying drawing be interpreted merely as illustrative and not in a limiting sense.

Having thus described my invention, what I claim as new and desire to secure by Letters Patent, is:

1. A collapsible tie rack for attachment to a supporting surface, said tie rack comprising a pair of spaced supporting members, a mounting lug pivotally secured to each of said supporting members at the inner end thereof, an outer longitudinal element swingably mounted for horizontal movement on said supporting members at the outer ends thereof, said element having a plurality of hanger pins spaced therealong, and an inner longitudinal element independently pivotally mounted on said supporting members intermediate their ends for horizontal movement thereon, said inner longitudinal element having a plurality of spacing pins secured along the upper surface thereof.

2. A collapsible tie rack for attachment to a supporting surface, said tie rack comprising a pair of spaced supporting members, a mounting lug pivotally secured to each of said supporting members at the inner end thereof, an outer longitudinal element swingably mounted on said supporting members at the outer ends thereof, spacer members interposed between said supporting members and said outer element to dispose said outer element below said supporting members, said outer element having a plurality of hanger pins spaced therealong, and an inner longitudinal element swingably mounted on said

supporting members intermediate their ends, said inner longitudinal element having a plurality of spacing pins secured along the upper surface thereof, all constructed and arranged so that said pair of supporting members and said inner and outer longitudinal elements may be swung inwardly toward said supporting surface.

3. A collapsible tie rack for attachment to a supporting surface, said tie rack comprising a pair of spaced supporting members, a mounting lug pivotally secured to each of said supporting members at the inner end thereof, an outer longitudinal element swingably mounted on said supporting members at the outer ends thereof, spacer members interposed between said supporting members and said outer element to dispose said outer element below said supporting members, said outer element having a plurality of hanger pins spaced therealong, an inner longitudinal element swingably mounted on said supporting members intermediate their ends, spacer members interposed between said supporting members and said inner element to dispose said inner element above said supporting members, said inner element having a plurality of spacing pins secured along the upper surface thereof, all constructed and arranged so that said pair of supporting members and said inner and outer longitudinal elements may be swung inwardly toward said supporting surface.

PHILIP PESTYNER.
